UNITED STATES PATENT OFFICE.

GILBERT C. SHEPHERD, OF NEW YORK, N. Y.

TEMPORARY BINDER.

No. 840,665.

Specification of Letters Patent.

Patented Jan. 8, 1907.

Application filed August 13, 1903. Serial No. 169,356.

To all whom it may concern:

Be it known that I, GILBERT C. SHEPHERD, a citizen of the United States, and a resident of the city of New York, borough of Brooklyn, county of Kings and State of New York, have invented a new and useful Improvement in Temporary Binders, of which the following is a specification.

The object of my invention is to provide a binder of this class in which the leaves or pages are held firmly by pressure and in which said pages may be easily removed or replaced. This is accomplished by means of the mechanism hereinafter described.

In the drawings forming a part hereof, Figure 1 is a plan view of my improved binder. Fig. 2 is a section taken on the line 2 of Fig. 1 looking in the direction of the arrows. Fig. 3 is a plan showing the back plate with some of the mechanism secured to it, parts being shown in section. Figs. 4 and 5 are detailed views showing parts of the mechanism.

Throughout the various views similar reference characters designate similar parts.

The binder 1 is provided with a back plate 2, which is formed with an integral and centrally-located longitudinal web 3, which extends from near one end a little more than half-way, where it terminates in an enlarged end 4, which is provided with a cylindrical bore 5. This web 2 is also provided with a second enlargement 6 near its other end, which projects above and on each side of said web, as will hereinafter appear.

Overlapping and extending beyond the enlargement 4 are parallel webs 7 and 8, which serve to stiffen the structure and protect the clamping mechanism; and between the other ends of these webs 7 and 8 is a lug 9, with a bore 10, which is concentric with the axis of the bore 5. This lug 9 is connected with a longitudinal web 11 at one side, which terminates in a second lug 12 near one end of the back. The lugs 9 and 12 and the web 11 are preferably made integral with each other and the back 2. A lug 13, integral with the back 2, is placed symmetrical with the lug 12 with regard to the axis of the bores 5 and 10. Transverse flanges 14 and 15 extend from the end of the back 2 from the lugs 12 and 13, and a similar flange 16 is placed at the other end of the back 2 with longitudinally-extending lugs 17 and 18. The flanges 14, 15, and 16 are about the same height as the edges of the back 2, which is concaved on the face the lugs protrude from, and the lugs 12, 13, 17,

and 18 extend above these flanges, as shown in Fig. 2. Guide-plates 19 and 20, with upwardly and inwardly turned flanges 21 and 22, are secured to the lugs 12 and 13 and 17 and 18, respectively, and these plates 19 and 20 protrude beyond the edges of the back 2, as shown in Fig. 3.

A key 23, which may be an ordinary clock-key, engages a spindle 24, with a collar 25, which forms a journal in the bore 10, and beyond this collar the spindle is reduced at 26 to form a second collar 27, beyond which the spindle is screw-threaded at 28 to the second journal 29, which is at the end of the spindle 70 and fits in the bore 5. A slotted plate 30 fits the reduced portion 26 and rests against the lug 9 to hold the spindle 24 against all motion in the direction of its axis.

A nut 31 engages the screw-threads 28 and 75 slides backward and forward on the back 2 when the spindle 24 is rotated. This nut 31 is preferably rectangular in cross-section and is provided with ratchet-teeth 32 on each side, and its inner end is formed into a cam 33, 80 which is adapted to engage and separate the upwardly and forwardly disposed ends of the spring-dogs 34 and 35, which are fixed at 36 to the web 3. The dogs 34 and 35 are each bent upwardly and then downwardly, as 85 shown in Fig. 2, so as to engage the pawls 58 and 59, as will appear below.

The clamping members 37 and 38 may be of any suitable form, although they are preferably made, as shown, with curved sides 39 and 40 and projecting bottoms 41 and 42, which have extensions 43, which are between the guides 19 and 20 and the flanges 14, 15, and 16, and these extensions 43 are connected with the curved sides 39 and 40 by 95 means of webs 44, so that the clamping members 37 and 38 may slide transversely of the back 2, but in no other direction. Telescoping binding-fingers 45, 46, 47, and 48 unite the upper edges of the clamps 37 and 38. 100 While only four such fingers are shown, it is obvious that as many may be used as desired. Running parallel with these fingers and below the plane they occupy are rods 49, which each have one end secured to the sides 39 and 40, respectively, and the other end of each rod passes through a hole 51 in the web 3. Springs 52 encircle these rods, each having one end pressing against the web 3, and the other against the sides 39 and 40. Only 110 one set of such springs and rods are shown for convenience, although it is preferable for

some purposes to use several sets each identical with those described above. These springs tend to separate the clamps 37 and 38, which are brought together against their action, as is apparent.

At suitable intervals the clamps 37 and 38 are provided with depending lugs 53, from which protrude studs 54, to which are pivoted toggle-levers 55, the other ends of said levers being connected to a slide 56. The studs 54 are preferably screw-threaded at their lower ends to engage the bottom 41 and 42, and the levers 55 are connected to the slide 56 by rivets, which also pass through small washers 57.

Centrally located on the slide 56 are pivoted pawls 58 and 59, which are pivoted at 60 and provided with teeth 61, which are adapted to engage the teeth 32 on the nut 31. These pawls are also provided with cams 62, which are adapted to engage the ends of the dogs 34 and 35. A spring 63 at the rear of these pawls tends to bring them together, so that the teeth 61 are separated against the action of this spring.

The slide 56 is held in position and against all movement save that in the direction of its length by bands 64, which are secured to the lugs 9 and 6 by pins 65, which pass through perforations therein, as clearly shown in Figs. 1 and 2.

In Fig. 6 is shown a portion of a page 66 with a slot 67, adapted to fit over one of the telescoping fingers, and the lines 68 in Fig. 1 show the maximum the binder 1 may be opened to receive pages 66. The lines 69 show the minimum opening.

From the above the operation of my improved binder will be readily understood.

Assuming the parts to be in the position indicated in Fig. 1, the pages 66 are properly inserted, as they may be each independently of the others, and when a sufficient number are in place the clamps 37 and 38 are brought together, thereby causing the toggles 55 to make the slide 56 move in the direction of the key 23. During this movement the pawls 58 and 59 are caused to spread outwardly by the cams 62, which ride over the ends of the dogs

34 and 35 and engage the teeth 32 on the nut 31, thereby locking the clamps 37 and 38 against the pages 66. This is ordinarily found sufficient; but should it be found desirable to clamp the pages more rigidly together this may be done by turning the key 23 and revolving the shaft 24, thereby bringing the nut 31 toward the key 23, together with the slide 56, and thereby further tightening the clamps 37 and 38. These clamps are separated by the action of the spring 52 when the nut 31 is moved away from the key 23 by turning the shaft 24, and when the cam 33 on this nut engages the dogs 34 and 35 it separates them and causes the pawls 58 and 59 to

separate against the action of the spring 63

and release the nut 31, so that the springs 52 are free to separate the clamps 37 and 38 with rapidity. The nut 31 is then brought forward until the dogs 34 and 35 are clear of the cam 33, when the clamps may be again closed, as described above. The key 23 is removed from the binder at any time when pages are not being removed or inserted, as it is then unnecessary. From this it is apparent that my improved binder may be clamped and unclamped with rapidity and ease for the removal or insertion of pages and that all pages which are inserted will be securely held.

While I have shown and described one embodiment of my invention, it is obvious that many others may be made which employ its essential elements and utilize its advantages, which equivalent structures are covered by the following claims.

What I claim is—

1. In a temporary binder or similar device, a back, clamps sliding thereon, a slide, a nut under said slide, means for positively engaging and disengaging said nut and slide, toggle-levers connecting said clamps and causing the same to be fixed so that the clamps will hold pages without danger of removal.

2. In a temporary binder or similar device, a back, clamps sliding thereon, locking means for securing said clamps against the pages, means connecting said locking means with the said clamps, and means for engaging or disengaging said locking means and connecting means.

3. In a temporary binder or similar device, a back, clamps sliding thereon, a slide secured to said back, toggle-levers connecting said slide and clamps, a nut and means for causing the slide and nut to be engaged or disengaged.

4. In a temporary binder or similar device, a back, clamps sliding thereon, a slide, toggles connecting said slide and clamps, pawls pivoted to said slide, ratchet-teeth adapted to move in a direction parallel to said slide and means for causing said teeth to engage or disengage said pawls.

5. In a temporary binder or similar device, a back, clamps sliding thereon, a slide, toggles connecting said slide and clamps, movable ratchet-teeth, a spindle with means for operating said ratchet-teeth, and means on said slide adapted to engage and disengage said teeth.

6. In a temporary binder or similar device, a back, clamps sliding thereon, a slide, toggles connecting said slide and clamps, pawls with teeth and cams secured to said slide, a spindle, a nut on said spindle and ratchet-teeth and a cam on said nut.

7. In a temporary binder or similar device, a back, clamps sliding thereon, a slide, toggles connecting said slide and clamps, pawls with teeth and cams pivoted to said

slide, a spring tending to move said pawls together, dogs adapted to engage said cams secured to said back, a spindle and a nut with teeth, which are adapted to be engaged by 5 said pawls, and a cam adapted to be engaged by said dogs.

8. In a temporary binder or similar device, a back, clamps sliding thereon, springs tending to support said clamps, toggle-levers, and

means for causing said toggle-levers to move 10 said clamps against the action of said springs.

Signed at the city of New York, county and State of New York, this 12th day of August, 1903.

G. C. SHEPHERD.
